UNITED STATES PATENT OFFICE.

ROBERT KUNATH, OF JEFFERSON, SOUTH DAKOTA.

HOG OILER.

Application filed July 18, 1924. Serial No. 726,728.

To all whom it may concern:

Be it known that I, ROBERT KUNATH, a citizen of the United States, and resident of Jefferson, in the county of Union and State of South Dakota, have invented certain new and useful Improvements in Hog Oilers, of which the following is a specification.

My invention relates to hog oilers, and it is my purpose to provide an oiler which is 10 of simple, durable and inexpensive construction.

It is my purpose to provide an oiler of simple design which will serve to distribute oil to hogs of various sizes, and to spread 15 the oil over a majority of the surface of the hog's back.

Another object is to provide together with such an oiler, means for forcing all of the hogs passing under it to receive oil, irrespective of their size.

A still further object is to provide an oiler which has a maximum capacity and yet is cheap of construction.

A still further object is to provide certain 25 novel features of construction wherein means is provided for conveying the oil from the interior of the oiler, which serves as a container, to the exterior thereof, from whence it may be distributed to hogs.

With these and other objects in view, my invention consists in the construction, arrangement and combination of the various parts of my device, whereby the objects contemplated are attained as hereinafter more 35 fully set forth, pointed out in my claims and illustrated in the accompanying drawings, in which:

Fig. 1 is a longitudinal vertical section through the body of my oiler, the supporting posts being shown in elevation.

Fig. 2 is a vertical transverse section taken on the line 2-2 of Fig. 1.

Fig. 3 is a transverse sectional view through a runway, in which my oiler is installed.

Fig. 4 is a detail sectional view of the adjusting mechanism carried by one of the supporting posts, taken on the line 4-4 of Fig. 1.

Fig. 5 is a detail longitudinal sectional view through one of the oil-transmitting ducts, illustrating a slightly modified form thereof.

In order to achieve the main purpose of

my invention, which is the distributing of 55 oil to hogs of various sizes, I have conceived the idea providing an under surface against which the hog might rub. The surface is inclined so that the smaller hogs may contact against the lower portion thereof and the larger hogs may contact against 60 the upper portion thereof. By the hog passing under the oiling surface in both directions and exerting sufficient pressure thereagainst, it will thus be possible to 65 bring the oil in direct contact with the back from the spine to a point quite low on each side of the back of the animal. It is more essential that the oil be distributed to the animal there than to the lower portions of 70 the side because the hair is thicker there, and some of the excess oil will gradually work down onto the belly of the animal after the hog has been in contact with the oiler.

Some oilers have been designed utilizing the idea of distributing the oil to the hog from above, but all of these use a cylinder, the lower surface of which is practically 75 horizontal.

With the advantage of the inclined surface in mind I have evolved the conical-shaped container, which, when in use, is positioned so that the under surface is inclined at a substantial angle.

I have used the reference numeral 10 to indicate generally the lateral portion of the container, and the numeral, 11, to indicate the base or bottom, which may be bolted or otherwise suitably secured by means of 90

bolts, 12, to flanges, 13, formed on the lateral portion, 10. The portions, 10 and 11, have the collars, 14, formed thereon, which are designed to receive a pipe, 15, to serve as an axle. The container is pinned or otherwise secured to the pipe, 15. At its lower end the pipe, 15, is journaled in the bearing, 16, which has the downwardly-extending bifurcated arm, 17, embracing and pivoted by means of a bolt, 19, to the post, 18. At its other end the pipe, 15, is received between a post, 20, and a yoke, 21, in such a manner that it may slide vertically. Registering holes, 22 and 23, in the yoke and post respective are designed to receive 100 a pin or spike, 24, in order to support the pipe, 15, in any of its adjusted positions.

In order to convey oil to the interior of the

container an elbow, 25, may be threaded onto the end of the pipe, 15, wherein a funnel may be inserted for guiding oil into the pipe, 15. The openings, 26, in the lower end 5 of the pipe allow escape of the oil from the pipe into the interior of the container.

It is essential that means be provided for conducting the oil from the interior of the container to the outer surface thereof in 10 sufficient quantities as will be used without wasting any of the oil. It will be understood from the foregoing description that the container is rotatably mounted. I have provided the oil ducts, 27, extending from a 15 point near the base of the cone to a point spaced somewhat below the apex thereof. The ducts, 27, may be cast integrally with the container or may be formed of a channel of sheet metal soldered or welded thereto.

20 In the side, 10, of the container, within the ducts, 27, at their ends adjacent the base, 11, are the valve openings, 28, in which are received the ball valves, 29. The width of the duct, 27, is such that the ball valve is 25 imprisoned against movement longitudinally of the duct, but will drop sufficiently, when the duct has rotated to a position near the bottom of the container, to allow the oil to enter the duct through the valve opening, 28. As the container is rotated, the valve will run back to its seat in order to prevent the oil escaping back into the container, and when the duct has moved to a 30 position where the valve end is above the other end, the oil will run to that end and be discharged through the openings, 30, onto the surface of the container. From thence it will be seen that the oil will spread 35 toward the apex of the cone and downwardly along the sides to the under surface thereof. The oil is thus distributed from a point near the top of the cone, from whence it may spread so as to cover a maximum portion of the surface underneath the 40 container.

45 In order to aid in the distribution of the oil and to more effectively convey it to the back of the hog, the outer surface of the container is provided with burlap or other fabric covering, 31, which may be held in place by wirewrapping, 32.

The arms, 17, supporting the lower end of the shaft, 15, are extended rearwardly to a point where sufficient distance is provided 50 between the base, 11, and the post, 18, that the ordinary hog will not be caught therebetween as he attempts to pass under that portion of the oiler.

55 In many cases it is desirable to install the oiler in a runway in order to force all of the hogs passing therethrough to receive oil. Such a runway is shown in Fig. 3, in which the posts, 20, form a portion of a fence having the rails, 33. On the other side a 60 fencing, 34, may be provided. The post, 20,

is inclined in order to incline the axis of a gate, 35, which is hinged thereto at 36. By thus inclining the gate, 35, it will tend to swing to a position where it is coplanar with the axle, 15. As the hogs pass through the 70 runway they will nose the gate aside and the gate will tend to urge them against the oiler, the end of the gate offering the least resistance to pressure.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In a hog oiler, a rotatably mounted conical container, the under surface thereof being inclined from the horizontal, a hollow axle for the container adapted to transmit oil to the interior of the container, and means for conducting the oil in small quantities from the interior to the exterior of the container.

2. In a hog oiler, a rotatably mounted conical container, the under surface thereof being inclined from the horizontal, a hollow axle for the container adapted to transmit oil to the interior of the container, and oil ducts on the lateral portion of the container, extending from a position near the base thereof to a point spaced from the apex thereof, the ends of the ducts near the base thereof, being in communication with the interior of the container, and the other ends of the ducts being in communication with the exterior of the container.

3. In a hog oiler, a rotatably mounted conical container, the under surface thereof being inclined from the horizontal, means for transmitting oil to the interior thereof, and oil ducts on the lateral portion of the container extending from a position near the base thereof to a point spaced from the apex thereof, the ends of the ducts near the base thereof being in communication with the interior of the container, the other ends of the ducts being in communication with the exterior of the container.

4. In a hog oiler, a rotatably mounted conical container, the under surface thereof being inclined from the horizontal, means for conducting oil from the interior to the exterior thereof as the container is rotated, a gate under the container shaped to conform to the contour of the under portion of the container and mounted to swing away from the container, and means for returning the gate to position under the container.

5. In a hog oiler, a rotatably mounted container, the under surface thereof being inclined from the horizontal, oil ducts on the lateral portion of the container, the ends 130

of the ducts which are lowermost when under the container being in communication with the interior of the container, and the other ends being in communication with the exterior thereof.

6. In a hog oiler, a rotatably mounted conical oil distributor, the under portion thereof being inclined from the horizontal, and means for mounting the distributor so as to allow hogs to contact with the lower surface thereof.

7. In a hog oiler, a combined oil distributor and container having a central axle mounted at one end in a bearing having a pivotal mounting, and at its other end in

vertically adjustable relation to a supporting standard.

8. In a hog oiler, a combined oil distributor and container having a central axle mounted at one end in a bearing having a pivotal mounting, and at its other end in vertically adjustable relation to a supporting standard, said central axle being hollow and having communication with the interior of the container to allow filling thereof through said axle.

Signed at Jefferson, in the county of Union and State of South Dakota, this 7th day of July, 1924.

ROBERT KUNATH.
